US0D1112352S

(12) United States Design Patent (10) Patent No.: US D1,112,352 S
Xie et al. (45) Date of Patent: * Feb. 10, 2026

(54) DISPLAY SCREEN OR PORTION THEREOF
WITH A GRAPHICAL USER INTERFACE

(71) Applicant: Chime Financial, Inc., San Francisco, CA (US)

(72) Inventors: Erin Xie, San Francisco, CA (US); Aashna Agarwal, Mountain View, CA (US); Aoni Wang, Redwood City, CA (US); Braden Staudacher, Vancouver (CA); Dennis Jiang, San Francisco, CA (US); Lucy Liu, Vancouver (CA)

(73) Assignee: Chime Financial, Inc., San Francisco, CA (US)

() Term: 15 Years

(21) Appl. No.: 29/868,535

(22) Filed: Dec. 6, 2022

(51) LOC (15) Cl. 14-04

CLAIM

The ornamental design for a display screen or portion thereof with a graphical user interface as shown and described.

DESCRIPTION

The FIGURE is a front view of a display screen or portion thereof with a graphical user interface showing our new design.

The outermost broken line shows the display screen or portion thereof and forms no part of the claimed design. All other broken lines show portions of the graphical user interface and form no part of the claimed design.

1 Claim, 1 Drawing Sheet
